UNITED STATES PATENT OFFICE.

CHARLES ADAMS, JR., AND WALTER A. ADAMS, OF WEEHAWKEN, NEW JERSEY.

SPARK PLUG.

Application filed September 4, 1919. Serial No. 321,543.

To all whom it may concern:

Be it known that we, CHARLES ADAMS, Jr., a citizen of the United States, residing at Weehawken, in the county of Hudson and State of New Jersey, and WALTER A. ADAMS, a citizen of the United States, residing at Weehawken, in the county of Hudson and State of New Jersey, have invented certain new and useful Improvements in Spark Plugs, of which the following is a specification.

This invention relates to a high tension ignition plug for internal combustion engine ignition, and has for its object visual indication of short circuits in such ignition system.

In the devices of this kind heretofore known the ignition spark-gap is formed by a pair of terminal members, one of which is directly grounded on the engine on which one terminal of the battery is also grounded, the indicating device being interposed between the other terminals. This arrangement has the defect that it is not possible with it to detect an ordinary short circuit around the spark-gap or other trouble of the circuit at the spark-plug.

The principal object of this invention is to provide a visual spark-gap on the positive or ingoing side of the spark-plug whereby the ingoing current may be sighted upon any plug in advance of its passing the ignition point so that in the absence of a spark at the visual point it will indicate an absence of ignition current at the terminal points of the plug.

Other objects of the invention will appear as the description proceeds; and while herein minute details of the invention are described, the invention is not limited to these, since many and various changes may be made without departing from the scope of the invention as claimed.

In the accompanying drawing, showing by way of example, one of many possible embodiments of the invention,

Figure 1 is a longitudinal sectional view of a spark-plug having our improved indicating means thereon, the connections thereof being shown diagrammatically.

Fig. 2 is an enlarged sectional view of the indicating means;

Figs. 3 to 5 are plan, side elevation and bottom view respectively of the spark-plug.

The spark-plug base 10 is screwed into

the engine cylinder in the usual way and is, therefore, grounded upon the engine as indicated at G, and has a bore 11 passing therethrough and provided interiorly with an intermediate annular seat 14, threads 15 at its upper part, and a flared lower end 16. A porcelain insulator 18 is disposed in said bore and provided with an intermediate enlargement 19, a pair of projections 20 at its lower end, a binding screw recess 21, an intermediately shouldered visual spark-gap chamber recess 22 at its upper end, a lateral window 23 communicating with said spark chamber recess, and a pair of small longitudinal bores 25 extending from said recesses 21 and 22 respectively and out through said projections 20 respectively. A threaded bushing 28 provided with tool receiving faces 29 engages with said threads 15 of said bore. Asbestos packings 30 and 31 disposed between the upper and lower parts of said enlargement 19 and said bushing 28 and seat 14 respectively hold said porcelain insulator everywhere spaced from said base and bushing.

A binding screw 35 is threaded into said binding screw recess 21 and provided with binding nuts 36 and 37. A straight terminal wire 39 is secured to said screw 35 and passes through one of said small bores 25 and has a lower projecting end 40. A hooked terminal wire 43 passes through the other small bore 25, and has its upper end terminating in said spark-gap chamber 22 and its lower end hooked as at 44 and disposed near said projecting lower end 40 to form an ignition spark-gap 45.

A spark-point plug 47 (Fig. 2) cemented in the lower end of said spark-gap recess 22 is secured to said hooked wire 43 and is provided at its upper end with a sparking point 48. A glass tube 49 on the shoulder 50 of said spark-gap recess closes said window and extends to the top of the recess. A connecting strip 51 (Fig. 1) secured by means of a screw 52 to the side of said base 10 is provided with a sight-opening 53 alined with said window 23, and has an angularly upper portion 54 disposed over said spark-gap chamber and provided with a threaded opening 57 (Fig. 2). A threaded sparking pin 58 is disposed in said threaded opening and has a tool slot 59 in its upper end, and has its lower end 60 pointed and co-operating with said sparking point 48 to provide a

visual spark-gap 62 alined with said window 23, and sight opening 53. A locknut 64 is provided on said pin.

A source of current, as for instance the 5 storage battery 70 has its negative terminal grounded on the chassis of the automobile, as indicated at G²; and an electrical connection 71 connects the positive terminal to said binding screw 35 and has an induction 10 coil 74 and timing distributor 75 interposed therein.

The spark plug is secured in the engine cylinder and connected up and operated in the ordinary way. If the current is passing 15 and the sparking taking place properly, there will be sparking at the visual spark-gap 62 and this can be ascertained by sighting through the opening 53 and window 23. Should the circuit be open anywhere, 20 obviously no spark will show at the spark gap 62, and trouble will be thereby indicated. Should there be any short circuit between the conductor 71 or either terminal 40 or 43 and the base 10 or engine cylinder, 25 the visual spark-gap will also be short circuited, and no spark will show therein.

A careful examination of this improved spark plug will show that practically all spark-plug troubles will be indicated by 30 the absence of the spark at the visual spark-gap.

We claim as our invention:

1. In a spark plug, a metallic base; an insulating member disposed in said base 35 provided with a spark gap chamber open at one end, said chamber having a translucent wall portion; means supported by and grounded on said base for connecting the base and insulating member and closing 40 the open end of the spark gap chamber and permitting view of the translucent wall portion of the spark gap chamber from the exterior of the spark plug; a spark-point plug operatively arranged in the spark gap 45 chamber; and a sparking pin operatively connected to said connecting means for co-operating with said spark-point plug for providing a spark gap in said chamber.

2. In a spark plug, a metallic base; an insulating member disposed in said base provided with a spark gap chamber open at 50 its outer end, said chamber having a translucent side wall portion; means supported by and grounded on said base for connecting the base and insulating member and having a sight opening registering with said translucent wall portion; a spark-point plug operatively arranged at the inner end 55 of the spark gap chamber; and a sparking pin operatively connected to said connecting means for cooperating with said spark-point plug for providing a spark gap in 60 said chamber.

3. In a spark plug, a metallic base; an 65 insulating member disposed in said base

provided with a spark gap chamber open at its outer end and having a sight opening; a glass lining for the side walls of the spark gap chamber; means supported by and grounded on said base for connecting the 70 base and insulating member and closing the outer end of the spark gap chamber and having an opening registering with the sight opening of said chamber; a spark-point plug operatively arranged at the inner 75 end of the spark gap chamber; and a sparking pin operatively connected to said connecting means for cooperating with said spark-point plug for providing a spark gap 80 in said chamber.

4. In a spark plug, a metallic base; an insulator disposed in said base and provided with a spark-gap chamber having a window therein; a cylindrical glass tube open at both ends and lining the sides of 85 the chamber and covering said window; a connecting strip supported and grounded on said base and having a portion closing the outer end of the chamber and holding said tube in place and provided with a 90 threaded opening disposed over said chamber; a spark-point plug in said chamber; and a sparking-pin adjustably received in said threaded opening and supported by 95 said strip and having its point disposed in said chamber and cooperating with said plug to provide a visual spark-gap.

5. In a spark plug, a metallic base; an insulating member disposed in said base provided with a spark gap chamber open 100 at one end, said chamber having a translucent wall portion; a recess in the outer end of the insulating member; means supported by and grounded on said base for connecting the base and insulating member 105 and closing the open end of the spark gap chamber and permitting view of the translucent wall portion of the spark gap chamber from the exterior of the spark plug; a terminal wire extending through the insulating member having one end in the spark gap chamber and its opposite end located externally of the insulating member at the inner end of said member; a spark-point plug on said wire located in the spark gap 110 chamber; a sparking point operatively connected to said connecting means and extending into the spark gap chamber for co-operating with said spark point plug; binding means in said recess of the insulating member; and a terminal wire extending through the insulating member having one end secured to said binding means and its opposite end located externally of the insulating member and operatively adjacent to the external end of the first mentioned 115 terminal wire.

6. In a spark plug, a metallic base; an insulating member disposed in said base provided with a spark gap chamber open 120

at its outer end and a recess adjacent to the spark gap chamber; the spark gap chamber having a sight opening therein; a translucent lining for the side walls of the 5 spark gap chamber; a metallic strip supported by the base at one side thereof and grounded thereon for connecting the base and insulating member and closing the outer end of the spark gap chamber; said 10 strip having an opening therethrough registering with the sight opening of the spark gap chamber; a terminal wire extending through the insulating member having one end in the spark gap chamber and its 15 opposite end located externally of the insulating member; a spark point plug on said wire located in the spark gap chamber;

a sparking point extending through said strip into the spark gap chamber for cooperating with said spark point plug; 20 binding means in said recess of the insulating member; and a terminal wire extending through the insulating member having one end secured to said binding means and its opposite end located externally of the insulating member and operatively adjacent to the external end of the first mentioned 25 terminal wire.
